UNITED STATES PATENT OFFICE.

CHARLES FAYER, OF FLUSHING, NEW YORK, ASSIGNOR TO WAPPLER ELECTRIC COMPANY, INC., A CORPORATION OF NEW YORK.

ELECTRICALLY-OPERATED HAIR-CURLING MACHINE.

Application filed November 23, 1926. Serial No. 150,184.

My invention relates to electrically operated hair curling machines, of a type suitable for use in permanently waving and curling the human hair, my special purpose being to produce a machine for operating a large number of individual curlers heated separately and by means of currents of very low voltage and each curler being thoroughly grounded, so as to completely eliminate, or at least reduce to a minimum, the chances for shocks, burns, or other injuries incidental to the use of my machine, or to the hair curlers controlled thereby.

I also seek to give my machine such construction, and to so arrange and adapt its various parts as to accomplish a number of distinct advantages, among them being the following:

I. To employ a large distributing head, preferably suspended overhead after the manner of a chandelier, and so arranged that within reasonable limits any desired number of curlers can be connected with it and detached from it independently of each other, by means of plug connections or the like, each individual curler and the conducting cord for energizing it being held captive by and supported from the distributing head, even when electrically disconnected therefrom.

II. To arrange the various individual curlers and their immediate connections in a number of distinct groups, the curlers of each group being adapted for conjoint use as for instance in curling the same head of hair, so that all or any desired number of the curlers of each group may be used simultaneously, the other curlers of the same group being rendered idle.

III. To bring the respective groups of hair curlers under control of a number of separate hand switches, each switch controlling one group, so that the operator, by throwing a particular switch, can bring some one of the groups into action, practically as a unit.

IV. To provide the several groups of curlers with visual signalling members, or equivalent indicating devices, one for each group, so as to enable the operator to readily ascertain, preferably by a glance at the distributing head, whether or not a particular group of the hair curlers is in action, or idle.

V. To provide each individual curler and the conducting cord for energizing the same with a counterbalance of suitable form and conveniently arranged, to keep the curler normally in a predetermined position relatively to the hair upon which the curler is used, in such manner as to maintain the curler substantially upright while in active use.

VI. To provide the distributing head with a number of safety fuses, each controlling one of said groups of hair curlers and so arranged as to be readily accessible for purposes of inspection and replacement.

VII. To simplify the mechanism of the distributor and to so connect the various mechanical and electrical parts thereof as to enable the same to be inspected, removed and replaced with a minimum of time and labor; and to conceal some of said parts as far as practicable, in instances where they would otherwise be unsightly.

Other objects of my invention are brought out below, in connection with the description of the various electrical and mechanical parts and their various combinations.

Reference is made to the accompanying drawing forming a part of this specification, and in which like reference characters indicate like parts throughout the several figures.

Figure 1 is a fragmentary elevation of my device.

Figure 2 is a fragmentary section on the line 2—2 of Figure 1 looking in the direction indicated by the arrows, certain parts being shown diagrammatically.

Figure 3 is a fragmentary section indicating the manner in which certain parts are supported upon a center post.

Figure 4 is a vertical section through one of the counter weights and parts immediately associated therewith.

Figure 5 is a fragmentary elevation of one of the hair curlers, and indicates the manner in which it is suspended.

Figure 6 is a section on the line 6—6 of Figure 1, looking in the direction indicated by the arrows, and showing the structure of one of the conducting cords used for energizing the hair curlers.

A step-down transformer 6 is provided with a primary winding 7 and a secondary

winding 8, as indicated diagrammatically in Figure 2. The primary winding 7 is connected with alternating current leads 9 and 10, in the usual manner.

5 The primary winding 7 is energized by alternating currents of the kind ordinarily employed in houses for the purpose of lighting lamps or driving machinery. The currents generated within the secondary 10 winding 8 are of very low tension, preferably not more than ten or twelve volts, or even less.

One end of the secondary winding 8 is grounded by connecting it with a wire 11, 15 leading to the ground at 12.

Connected with the grounded end of the secondary winding 8 is a conducting cable 14, and connected with the opposite end of the secondary winding 8, and thus ungrounded, is a conducting cable 15. The cables 14 and 15, properly insulated, are for convenience united into a twin conductor 13, preferably of considerable size.

The grounded cable 14 leads to a metallic 25 distributing disk, shown more particularly in Figures 2 and 3. Below the distributing disk 16 is another distributing disk 17, and between these two disks is an insulator 18 having an annular form, as indicated more 30 particularly in Figure 3.

The insulator 18 encircles a center post 19, and spaces the distributing disks 16 and 17 apart, so as to maintain them parallel with each other.

35 The center post 19 depends from a ceiling piece 20, secured against the under side of a ceiling 21, as indicated in Figure 1.

Mounted upon the center post 19 is a supporting bracket 22, used for supporting the 40 cable 13, as indicated in Figure 1.

The center post 19 is at its lower end provided with a head 23, and resting upon this head is a base plate 24, located a little below the distributing disks 16 and 17.

45 Carried by the base plate 24 is an annular wall 25, and mounted upon this wall is a top plate 26.

The base plate 24, the annular wall 25 and the top plate 26, together constitutes a 50 box-like structure for holding a number of other parts, and which I designate generally as a distributing head.

Mounted upon the base plate 24 are a number of tubular posts 27, each provided at 55 its lower end with a threaded portion 28 which extends through a hole in the base plate 24, as indicated at the bottom of Figure 4. The threaded portion 28 carries two nuts 29, whereby the tubular post is secured 60 firmly upon the base plate.

Each tubular post 27 carries at its upper end a bracket 30, and journaled upon this bracket is a pulley 31. A fender 32 is supported by all of the tubular posts 27, and 65 serves to conceal as well as to protect the

pulleys 31 and parts immediately associated therewith.

Loosely encircling each tubular post 27 is a counterpoise 33, having the form of a substantially cylindrical weight, as indicated 70 more particularly in Figure 4.

Connected with each counterpoise 33 is a supporting cord 34, which extends over the pulley 31 and down through the tubular post 27, as shown in Figure 4.

75 Each supporting cord 34 carries at its lower end a clip 35, used as hereinafter described to support a conducting cord through which a hair curler is energized. The function of the supporting cord 34 is purely mechanical, its chief purpose being to connect the counterpoise 33 with certain parts to be balanced thereby.

80 A few hair curlers are shown at 36, and in this instance are all alike. I will not describe the structure of these curlers in detail, as it constitutes no part of my invention here under discussion.

85 Each hair curler 36 carries a heating coil 37, connected with and energized by a cord conductor 38.

90 Each cord conductor 38 is connected with a plug 39, and by means of this plug 39 the cord conductor may be readily connected with and disconnected from some one of a 95 number of contact sockets 40.

I do not deem it necessary to describe the 100 plugs 39 and sockets 40, further than to say that they are of the type conventionally used in many arts for making and breaking electrical connections more or less analogous to the ones here contemplated.

In the particular mechanism here illustrated, provision is made for supplying low tension currents to forty-eight hair curlers, arranged in eight groups, of six curlers each. Various other parts, each associated with a single curler, are likewise arranged into eight groups, of six each. For instance, there are forty-eight counterbalances 33, forty-eight tubular posts 27, and forty-eight cord conductors 38, all arranged in groups of six, and coating with the hair curlers, similarly grouped as above described.

110 Mounted upon the annular wall 25 are a number of pilot lamps 41 and a number of hand switches 42, there being one pilot lamp and one switch for each group of the hair curlers and parts immediately associated therewith. This means, of course, that for the forty-eight hair curlers and forty-eight cord conductors for energizing the same, there are eight pilot lamps and eight hand switches. Each hand switch controls a group of hair curlers, and each pilot lamp 41 indicates from time to time the condition of that group, the various groups being in great measure independent of each other.

115 Mounted upon the distributing disk 16 are a number of safety fuses 45, one for each 120

group of hair curlers. Each fuse 45 is connected with the disk 16 by a wire 44. From each fuse 45 a wire 46 leads to the hand switch 42 associated with the same group of hair curlers. From the hand switch a wire 47 leads to the pilot lamp 41 of the same group. From this pilot lamp a wire 48 leads to the distributing disk 17, and is connected with a number of sockets 40, above described. From the lamp 41 another wire 48 leads to the sockets 40, so that the sockets are connected in parallel with each other, after the manner in which incandescent lamps are usually connected. Thus for each group of six hair curlers there are provided six sockets 40 and six plugs 39.

My purpose in grounding one end of the secondary winding 8, as above described, is to avoid the possibility of developing high potentials in any part or parts of my mechanism. Thus not only do I ground the cable 14, but I carry the same general idea still further and practically ground the metallic body portion of each hair curler 36 and also practically ground the outer or exposed metallic portion of the cord conductor 38, as I will now describe.

Referring more particularly to Figure 6, it will be noted that the cord conductor 38 is provided with an outer sheath 50, within which is an insulating member 51 of tubular form, and within this insulating member is a metallic conductor 52, preferably stranded. The outer sheath 50 is made of metal, preferable fine wire woven into cylindrical form and is connected directly with the outer or exposed body portion of the hair curler 36.

The cord conductor 38 is essentially a twin conductor, the two conducting members being those numbered 50 and 52, as may be understood from Figure 6. This cord conductor is so connected with the plug 39, and this plug is so co-related to its mating socket 40, that when the plug is inserted into the socket the conductor 52 is brought into metallic communication with the wire 46, which leads to the distributing disc 16, this wire and disc being ungrounded; the metallic sheath 50, however being brought into communication with the wire 48 which leads to the distributing disk 17, which grounded.

By this arrangement every exposed portion of the cord conductor 38 is necessarily grounded at all times, and it becomes impossible to develop at any time during the operation of the machine, any substantial difference of potential between the earth on the one hand and the hair curlers 36 and their cord conductors 38, on the other.

It should be borne in mind that the grounding of the disc 17, through the cable 14 and ground wire 11, grounds every part connected immediately and directly with the disk 17.

So long as the machine is idle and inactive,

the hand switches 42 are open and the lamps 41 are de-energized, and the apparatus remains in this condition until ready for use.

Suppose, now, that the operator wishes to use the apparatus, say, for curling a head 70 of hair. For this purpose he may see proper to employ only one group of curlers, but he is not limited to a single group, as he can use two or more groups if he sees proper to do so. More than one operator can use the 75 machine at the same time, each operator employing as many groups as he sees proper. In fact, an operator can use less than an entire group, or even can use a single curler or any number less than a group of six, as 80 occasion may require.

To use a single group of six curlers, the operator prepares the curlers and places upon or within them the portions of hair to be curled.

The counterpoises 33 serve to maintain the supporting cords 34 taut, so as to support the outer or free ends of the curlers 36, and thus to maintain substantially vertical the curlers in actual use. These preliminaries being arranged, the operator closes the switch of the particular group of hair curlers to be energized.

In thus closing the switch the current is turned on, through the particular curlers of the group now in use, and the pilot lamp of this group is lighted up, making an indication visible to the eye that this group is being energized.

The operator or any other person by a 100 glance at the pilot lamp can ascertain the condition of the apparatus, to the extent at least of determining what particular group or groups of the hair curlers are for the time being in active use.

If the operator wishes to use less than a single group of the curlers, he pulls out enough of the plugs 39 to leave the required number he wishes to use, and then he closes the switch of this particular group.

It will readily be seen, therefore, that my machine can be used with any desired number of hair curlers, from one to the maximum number for which the machine is built, in this instance, forty-eight.

Whenever the plugs 39 are pulled out in order to prevent the curlers from being energized, the plugs are simply allowed to hang down idly, being supported by their respective supporting cords 34.

The safety fuses 45 are current operated, and adapted for currents of the amperage suitable for heating the hair curlers. One safety fuse is provided for each of the above mentioned groups, of six hair curlers each. If for any reason the current through any particular group becomes too heavy during the use of the apparatus, the safety fuse 45 of that particular group opens the circuit of that particular group alone.

I do not limit myself to the particular mechanism shown, as variations may be made therein without departing from my invention, the scope of which is commensurate with my claims.

Having thus described my invention, what I claim as new and desire to secure by Letters Patent is as follows:

1. In a device of the character described the combination of a center post, means for suspending said center post, a base plate carried by said center post and having the proximate form of a disc, an annular wall carried by a base plate and therewith forming a box like member, a pair of distributing discs supported upon said center posts and insulated from each other, said distributing discs being housed within said box like member, and means for energizing said distributing discs.

2. A device of the character described comprising a distributing head, a plurality of posts mounted upon said distributing head and extending upwardly therefrom, a pulley supported by each post, a supporting cord engaging said pulley, a substantially cylindrical weight connected with each supporting cord and loosely encircling the post associated therewith, and an electrically energized mechanism connected with each supporting cord and depending therefrom, and

means for energizing said electrically energized mechanism.

3. A device of the character described comprising a base plate, means for supporting said base plate, a plurality of tubular posts carried by said base plate, pulleys carried by said tubular posts, a supporting cord extending through each of said tubular posts and engaging the pulley carried thereby, a substantially cylindrical weight encircling each tubular post and supported by the supporting cord extending therethrough, and an electrically energized mechanism connected with each supporting cord and depending therefrom, each electrically energized mechanism being balanced by one of said substantially cylindrical weights.

4. A device of the character described comprising a center post of substantially cylindrical form, an annular member of insulating material encircling said center post and supported thereby, a pair of distributing discs carried by said annular member of insulating material and spaced apart, and electrical connections to said distributing discs, for the purpose of energizing the same.

Signed at Long Island City, N. Y., in the county of Queens and State of New York, this 20th day of November, 1926.

CHARLES FAYER.
